Inventor,
Henry M. Sheer
By Vernon G. Hodges
his Attorney

UNITED STATES PATENT OFFICE.

HENRY M. SHEER, OF QUINCY, ILLINOIS.

RADIATOR FOR HOVERS OR BROODERS.

Application filed January 7, 1924. Serial No. 684,852.

To all whom it may concern:

Be it known that I, HENRY M. SHEER, a citizen of the United States, residing at Quincy, in the county of Adams and State 5 of Illinois, have invented certain new and useful Improvements in Radiators for Hovers or Brooders, of which the following is a specification.

My invention relates to an improvement 10 in radiators for hovers or brooders.

The object is to provide means for uniformly heating and quick circulation of the air, as well as perfect ventilation of the area being heated; and, incidentally, to 15 guard the flame against undue and irregular drafts of air, and to afford safety and to create a healthy atmosphere for the chicks.

In the accompanying drawings:—

Fig. 1 is a section showing the relation 20 between the canopy and the radiator;

Fig. 2 is a section through a form of the radiator;

Fig. 3 is a top plan view; and

Figs. 4 and 5 show slight modifications. 25

In the construction shown in Figs. 1, 2 and 3, I propose to employ a fixed hollow body B, and in the most approved form this will taper, or have the shape of an inverted truncated cone as shown in Figs. 1, 2 and 4, 30 although obviously it might be cylindrical as shown in Fig. 5. The hollow body B will also be firmly fastened to the oil-well or oil-feed pipe 1 of the burner A, whichever may be found most desirable.

The tapered shape of the hollow body B 35 offers the following advantages, to wit: greater space for the air intake tubes C, permitting the use of larger tubes; greater heat radiating surface at the top where the largest amount of radiation is needed, and 40 correspondingly less radiation at the bottom where less heat is required; and greater area for the outlet of the products of combustion permitting the use of a narrower space when constructed as shown in Figs. 1, 45 2 and 4.

The tubes C project downwardly from a removable cover D. This cover is in the form of a disk, and when made as shown in 50 Figs. 1 and 2 rests upon, and a little above, the upper edge of the chamber B to afford space between the two for the easy escape of the products of combustion, but when formed as shown in Fig. 4, with the small 55 holes 2 at the top of the chamber B', the

plate or disk D' rests directly upon the top of the chamber.

Still another advantage of this tapering form is, that the cover D or D' may be removed to give free and easy access to the 60 burner A, because of the larger top diameter of hollow body B. Furthermore, when made in this tapering form, the hollow body provides space for large down-draft tubes or intake tubes C, large enough in fact so that 65 the upper ends can be covered with from #24 to #26 mesh gauze screen 3, and still admit abundant air for the burner A. The gauze, however, is unnecessary, and the construction as illustrated even without the 70 gauze screen is absolutely safe, unless gasoline is deliberately squirted or poured into the air intake tubes C.

In my improved construction, the outlet 75 of the products of combustion is not retarded, the enlarged top of the tapering form of hollow body giving room for expansion of the products of combustion, so that the escape of the products of combustion is rather hastened than retarded; and this is particularly true of the heat travel to the edge of the canopy E, and the rapid warming of the air in brooder-house.

In Fig. 1, I have shown the relation of 80 radiator and canopy. The cover D prevents the direct heat of the burner or radiator from striking the canopy as in general practice, and this will somewhat reduce the heat radiation of the canopy into the brooder-house, but this loss of heat is more than off-set by the increased volume of heated air 85 that is forced out under the edge of the canopy due to the rapid travel of the products of combustion, together with the increased radiation of cover D and hollow body 90 B, the cover D acting as a deflector or baffle.

Thus a continual, rapid and uniform circulation of pure heated air is created in a very simple way, and by simple, mechanical instrumentalities. The device is so simple 100 that it lends itself effectively to the purpose, does not easily get out of order, and provides means for easy and quick accessibility to the burner.

I claim:

1. A device of the character described including a hollow body, a burner therein, and a cover having down-draft tubes terminating in the hollow body, said hollow body having means of escape of the heated air 110

- extending therearound and immediately below the cover.
2. A device of the character described including a hollow body, a burner therein, and a cover having down-draft tubes terminating in the hollow body, said hollow body having an annular outlet adjacent and immediately below the cover, the cover having its edges projecting outwardly over the edge of the hollow body forming a baffle-plate therearound.
3. A device of the character described including a hollow body, a burner therein, and a cover supported upon the hollow body and having down-draft tubes extending into the area between the wall of the hollow body and the burner and terminating at a point below the top of the burner, said hollow body having an annular outlet adjacent and immediately below the cover. ¹⁵

In testimony whereof I affix my signature
HENRY M. SHEER.
